Patented Dec. 25, 1962

194,271

GRIDDLE

Orville W. Larson, Evanston, Ill., assignor to General
Electric Company, a corporation of New York

Filed Aug. 21, 1961, Ser. No. 66,423

Term of patent 3½ years

(Cl. D44—1)

FIG. 1 is a top plan view of a griddle showing my
new design;

FIG. 2 is a front elevational view thereof; and

FIG. 3 is a side sectional view taken on lines 3-3 of
FIG. 1.

I claim:

The ornamental design for a griddle, substantially as
shown.
